FOREIGN PATENT DOCUMENTS

GB 2426490 11/2006

Primary Examiner — Cynthia Ramirez

(57) **CLAIM**

The ornamental design for a waste bag stand as shown and described.

DESCRIPTION

FIG. 1 is a front view of a waste bag stand showing my new design;

FIG. 2 is a rear view of the waste bag stand;

FIG. 3 is a left side view of the waste bag stand;

FIG. 4 is a right side view of the waste bag stand;

FIG. 5 is a top view of the waste bag stand;

FIG. 6 is a bottom view of the waste bag stand; and,

FIG. 7 is a top rear side perspective view of the waste bag stand.

1 Claim, 7 Drawing Sheets
